(57) CLAIM

The ornamental design for a lockbox, as shown and described.

DESCRIPTION

FIG. 1 is a perspective view of the design of the present invention;

FIG. 2 is a top view of the lockbox shown in FIG. 1;

FIG. 3 is a front view of the lockbox shown in FIG. 1;

FIG. 4 is a back view of the lockbox shown in FIG. 1;

FIG. 5 is a bottom view of the lockbox shown in FIG. 1;

FIG. 6 is a side view of the lock shown in FIG. 1;

FIG. 7 is a side view of the lock shown in FIG. 1;

FIG. 8 is a perspective view of a second embodiment of the design of the present invention;

FIG. 9 is a top view of the lockbox shown in FIG. 8;

FIG. 10 is a front view of the lockbox shown in FIG. 8;

FIG. 11 is a back view of the lockbox shown in FIG. 8;

FIG. 12 is a bottom view of the lockbox shown in FIG. 8

FIG. 13 is a side view of the lock shown in FIG. 8; and,

FIG. 14 is a side view of the lock shown in FIG. 8.

The portions of the Figures shown in phantom lines are not part of the claimed design but are for illustration only.
